UNITED STATES PATENT OFFICE.

JOHN H. HIGGINS, OF CHARLESTON, MAINE.

HARROW.

SPECIFICATION forming part of Letters Patent No. 393,156, dated November 20, 1888.

Application filed December 7, 1887. Serial No. 257,193. (No model.)

To all whom it may concern:

Be it known that I, JOHN H. HIGGINS, of Charleston, in the county of Penobscot and State of Maine, have invented a new and Improved Harrow, of which the following is a full, clear, and exact description.

My invention relates to a spring-tooth harrow; and it consists, principally, in forming the frame in two sections hinged together and adapted to be rigidly locked parallel to each other to improve the efficiency of the harrow in leveling the ground.

The invention also consists of the special construction of the harrow-frame and of the clips used in securing the spring-teeth thereto.

Reference is to be had to the accompanying drawings, forming a part of this specification, in which similar letters of reference indicate corresponding parts in all the figures.

Figure 1 is a plan view of my new and improved harrow. Fig. 2 is a front end elevation of the same. Fig. 3 is a broken plan view of the hinge-connection of the rear ends of the sections of the harrow; and Figs. 4, 5, and 6 show different forms of clips for holding the spring-teeth to the bars of the harrow-frame.

A A represent the two sections of the harrow, each composed of the head-piece *a* and bars *a' a'*, mortised into the head-piece *a* at right angles to said head-piece and parallel to each other. Upon the upper surface of the bars *a' a'* are secured by the clips B and bolts *b b* the spring-teeth C. The inner ends of the head-pieces *a* project past the inner bars, *a'*, as shown at *d*, to space the sections A, and these projections *d* have square abutting ends and are secured together by the heavy hinge D at their under surface, the said abutting ends serving to prevent either of the sections A from swinging upward above a level with the other section. One of the projections *d* is provided with a stud, *f*, or other fastening device for the plate *f'* of the other projection to engage for locking the sections A A rigidly together, so that they act as one frame. The rear ends of the sections A A are connected together by the irons E E', bolted to the bars *a' a'*, and formed at their adjacent ends with the projections *e e'*, pivoted together to form a hinge on the same level as the hinge D, so that the sec-

tions may be folded face to face without cramping either hinge. The plate *E'* is provided with a stop, *f''*, which, together with the abutting ends of the projections *d*, prevents the sections A A from opening or being turned one 55 above the other.

The clips B, for holding the spring-teeth C, may be of various forms, as illustrated in Figs. 4, 5, 6, and 7, each with diagonally-opposite holding flanges or projections for engaging the spring-tooth, so that the clip may be reversed when desired. The clip shown in Fig. 4 is a rectangular plate formed with downwardly-projecting flanges *d d* at its edges, between the diagonally-opposite corners of which flanges 60 the spring-tooth is held, and it is formed with a bolt-hole, *c'*, at each corner, which makes the clip reversible. The clip shown in Fig. 5 is S-shaped, with studs *e* projecting both above and below its ends, and is formed with two 70 bolt-holes, *e'*, so that it may be used either side up to cause either set of studs to engage the tooth. The clip shown in Fig. 6 is bent down at its corners to form the studs *g* thereat, which engage with and hold the tooth. Each tooth 75 is held by only two bolts, so that the wooden bars of the harrow are not unnecessarily weakened as would be the case if four bolts were used for each tooth, and the two bolts are arranged at opposite edges of the tooth, and the flanges 80 at the edges of the clips prevent the tooth from turning sidewise out of place.

The locking-plate *f'* is formed with a slot, *f''*, to engage with the stud *f* under the head thereof, so that the said plate and stud form a cheap 85 and efficient lock for the sections of the harrow; but any other form of lock might be used.

By adapting the sections of the harrow to be locked rigidly together the harrow becomes 90 much more effective in leveling the ground.

Having thus described my invention, what I claim as new, and desire to secure by Letters Patent, is—

1. The head-pieces *a a* of the sections A A, 95 extended, as shown at *d*, and formed with abutting ends and hinged together, in combination with a locking device, *f f'*, at the upper surface of the head-pieces, substantially as described.

2. The sections A A, formed of head-pieces *a a* and bars *a'*, and the plates E E', formed with projections *c c*, hinged together, in combination with the hinge D and locking device 5 *f f'*, the adjacent ends of the head-pieces *a* being extended and constructed to abut squarely against each other, and the plate E', formed with the stop *f'*, substantially as described.

JOHN H. HIGGINS.
